United States Patent Office

Des. 177,865
Patented May 29, 1956

177,865

CLOCK

Lawrence H. Wilson, Grosse Pointe, Mich., assignor to
General Time Corporation, New York, N. Y., a corpo-
ration of Delaware

Application September 7, 1955, Serial No. 37,830

Term of patent 14 years

(Cl. D42—7)

Fig.

Des. 177,865

PAGE 2

Fig. 2

Fig. 3

Fig. 1 is a front elevational view of a clock embodying my new design;

Fig. 2 is a perspective view of the clock; and

Fig. 3 is a side elevational view of the said clock.

I claim:

The ornamental design for a clock, substantially as shown.
